UNITED STATES PATENT OFFICE.

LEOPOLD STRASSER, OF NEW YORK, N. Y.

DESIGN FOR A WRIST-WATCH CASE.

Application filed July 30, 1924. Serial No. 10,320. Term of patent 3½ years.

To all whom it may concern:

Be it known that I, LEOPOLD STRASSER, a citizen of the United States, residing at the city of New York, county of New York, and State of New York, have invented a new, original, and ornamental Design for Wrist-Watch Case, of which the following is a specification, reference being had to the accompanying drawing, forming part thereof.

The figure is a front elevation of a wrist watch case embodying my new design. The shading in the inner portion of the figure indicates the glass or crystal of the watch case.

I claim:

The ornamental design for a wrist watch case as shown.

LEOPOLD STRASSER.
